Dees Sprague

Atty.

UNITED STATES PATENT OFFICE.

WILLIAM A. HERMANN, OF AUBURN, MAINE, ASSIGNOR TO MACLAUGHLIN-SWEET, INC., OF AUBURN, MAINE, A CORPORATION OF MAINE.

SHOE SHANK.

Application filed February 9, 1923. Serial No. 617,932.

To all whom it may concern:

Be it known that I, WILLIAM A. HERMANN, a citizen of the United States, residing at Auburn, county of Androscoggin, 5 State of Maine, have invented certain new and useful Improvements in Shoe Shanks, of which the following is a specification.

This invention relates to shoe structures and more particularly to the soles or instep structures thereof. Most shoes and especially women's shoes having high or relatively high heels require for the support of the foot and the shape of the shoe a rigid and very carefully shaped instep arch. 10

This is usually effected by the use of a reinforcement or shank of some sort. My invention may best be illustrated by a shank structure and preferably by certain special shank embodiments which combine 15 to give such increased arch support as well as form and finish without unreasonable expense.

One of the difficulties in reinforcing a shoe at this location results from the relation 20 of the stiff shank piece to the otherwise flexible materials embodied in this region of the shoe.

As worn the shoe must of necessity follow in part the natural flexion of the foot 25 in walking and it has been a difficult matter to get rigidity and support in a region like the instep immediately adjacent an area of flexion such as across the ball of the foot.

In shoes in accordance with my invention 30 I combine the elements or parts in such a manner as to accomplish this result without omitting or interfering with other known requirements or accepted desiderata common in conventional shoe practice.

As illustrative of my invention I have shown in the accompanying drawings certain structures and embodiments characteristic of my invention and well adapted to 35 illustrate the principles thereof. These also show some details preferable but not all essential to the various embodiments of which my invention is capable.

Throughout these drawings and the specification relating thereto, like reference characters are conventionally applied to indicate designated parts, and in the drawings:—

Fig. 1 is a side elevation of a shoe in accordance with my invention.

Fig. 2 a fragmentary section of a portion 55 of the sole thereof.

Fig. 3 a similar view in partial section.

Fig. 4 is a detail of a shank member.

Fig. 5 is a section on the line 5—5 of Fig. 4.

Fig. 6 is a cross-section on the line 6—6 60 of Fig. 2.

Fig. 7 a view of a sole partly opened up to indicate the disposition of parts.

In the drawings I have indicated at 1 a sole, at 2 an upper and at 3 a heel portion in usual assembly. The sole 1 is preferably integral and split from its heel portion 65 down to the ball to form two flaps 11 and 12. These flaps are coated with cement and adapted to be secured together.

In the form of shoe illustrated herein, I embody between the two flaps 11 and 12 a shank piece 4 which is permanently attached to the flap 12 in any suitable manner as by tacks, rivets or stitches. This shank piece 70 may be composed in part of a fibrous material but is of a considerable strength and hence usually of necessity of some considerable thickness. On account of its position beneath the inner surface of the sole its flattened upper portion does not produce any distortion or unevenness in the foot contacting surface of the sole but supports it uniformly and smoothly throughout. The outer flap 11 may be molded over the shank 75 piece 4 so as to conform to its external contour whatever that may be.

In the form shown the shank piece is in 80 its arched portion somewhat triangular in cross section and the sole therefor acquires through it the so-called "cottage type" shank, but without the usual difficulties of such types, as the shank is completely embedded as it were in an otherwise continuous and integral sole member.

While this shank is of great strength it 85 is in many cases desirable to supplement the shank by an additional inner shank 5 as shown in Figs. 2 and 3, which being fastened to the flap 12 clamps that flap between itself and the shank 4 so as to unify in a solid and combined structure the sole itself and the shank members, thus preventing any working or playing of the parts 90 and any consequent deformation or rupture of the shoe structure.

In the form of shank shown, I have indicated an extremely rigid type in which

an outer member 4' is formed of sheet metal. At its lower end this portion of the shank is formed as a V-shaped channel which runs down to the flattened portion adapted to 5 underlie the heel seat. Within this channel I locate a fibre filler 4². As appears in Fig. 4, this fibre filler runs out beyond the end of the metal casing 4' forming a somewhat splayed foot as appears in Fig. 3. This 10 extending foot makes a softened end for the shank which has in general a cushioning effect in the area X of the sole. Furthermore, being in itself soft and yielding it does not have the chiseling or cutting effect 15 on the sole 1 which would be the case if a harder material were carried to that region. In fact, when cemented in place this reinforcement becomes unified with the adjacent walls of the split sole and greatly 20 increases the wearing qualities and the possibilities of finish and shaping the sole.

While I have shown in the accompanying drawings and described in particular a somewhat specialized embodiment of my invention, it will be understood that the elements may be somewhat varied and somewhat variously combined. The shank member 4 may be entirely of fibre or steel or 25 wood or other suitable materials or may in some instances be omitted. In practice, the sole is rounded out and channeled in the ordinary manner. It is then split and the flap is preferably cemented back at once 30 so as not to interfere with the sewing of the sole. Where an inner shank is employed 35 it may then be tacked or sewed to the adjacent severed portion of the sole. The shoe

having been made, the shank piece 4 is then tacked or cemented or both within the sole and underneath the flap. After this 40 the flap is again cemented securely in place and formed down neatly over the enclosed shank member and after this the shoe may be finished in the usual manner. My invention is applicable to shoes of various 45 types and in turn, welt and McKay construction and in such produces a shoe giving an unusual support in the arch and all without involving any costly or inconvenient feature in the manufacture of the shoe. 50

What I therefore claim and desire to secure by Letters Patent is:—

1. In a shoe structure, an outer sole having a longitudinally split heel and shank, a shank piece disposed in said split and comprising a sheet metal channeled shell and an enclosed fibrous filler extended slightly beyond the lower end and sides thereof, and fastened through said sole and covered by the flap of the sole molded thereto and secured in place over it. 55

2. In a shoe structure, an outer sole having a longitudinally split heel and shank, a stiffener comprising a flattened heel and shank piece disposed thereon and a second shank piece disposed in said split, said shank pieces being each fastened to said interposed sole and covered by the flap of the split sole molded thereto and secured in place over it. 60 65 70

In testimony whereof I affix my signature.

WILLIAM A. HERMANN.
